UNITED STATES PATENT OFFICE

THEODORE W. KUPFER, OF ROCHESTER, NEW YORK

KEY GUARD

Application filed February 6, 1931. Serial No. 513,914.

This invention relates to an improved and simplified key guard which is adapted to be readily fastened to the inside of a door so as to engage the key projecting from the lock and prevent it from being dislodged thru the key hole from the outside in an attempt to unlock the door from without.

One of the objects of the invention is to provide an extremely simplified construction in order to make it inexpensive to manufacture.

Another object of the invention is to provide an improved and simplified method of fastening the key guard to the door which makes it possible for anyone to attach it in a minimum length of time.

Another object of the invention is to provide a construction and operation for the locking member of the guard which makes it extremely simple to operate.

Other objects and attendant advantages will become more readily apparent from the detailed description of one embodiment of the invention which follows, reference being had to the accompanying drawings in which

Figure 1 is a front elevation of a portion of a door with the door lock having my improved key guard attached thereto.

Figure 2 is an end elevation of the portion of the door and door lock with the key guard attached to it.

Figure 3 is a vertical sectional view of the key guard, the section being taken on the line 3x-3x of Figure 2.

Figure 4 is a vertical sectional view of the key guard and portion of the door, the section being taken on the line 4x-4x of Figure 1.

Figure 5 is a horizontal sectional view of the key guard, the section being taken on the line 5x-5x of Figure 4.

In the several figures of the drawings like reference numerals indicate like parts.

The key guard forming the subject matter of my present invention is so constructed that it combines simplicity of construction with simplicity of operation and when attached to the door forms a permanent fixture which cooperates with the lock in such an efficient manner that it prevents any attempt to un-

lock the door from the outside as long as the key is inserted into the lock on the inside of the door.

As illustrated in the several figures of the drawings the key guard comprises a vertical bracket 1 which has the locking plate 2 pivoted at the upper end thereof. The vertical bracket 1 has a rearwardly extending or offset lug 3 formed at the lower end thereof and in this lug is provided a suitable hole thru which passes the screw 4 that fastens the lower end of the bracket 1 to the door below the escutcheon.

The upper end of the bracket 1 is provided with a central slot 5 and at the bottom of this slot is struck up a rearwardly extending hook shaped lug 6 which is adapted to hook over the bottom edge of the key hole 7 provided in the escutcheon. When attaching the key guard to the door the lug 6 is first hooked into the key hole so that it engages the bottom edge thereof as above pointed out. The lug thus locates and anchors the upper portion of the bracket 1 in place on the escutcheon plate and with the addition of the screw 4 firmly holds the key guard permanently in place on the door.

Two eyes 8 and 9 are formed at the top of the vertical bracket 1, in each of which is mounted a pivot pin 10. These pivot pins extend to one side and have at their outer ends the eyes 11 and 12 pivoted thereon. The eyes 11 and 12 are formed on the inner end of the locking plate 2 and thus provide the pivotal means with which the locking plate 2 is mounted to swing on the vertical bracket 1.

At the rear of the bracket 1 along each side thereof are provided the guides 13 and 14. A slide 15 is mounted at the back of the bracket 1 and its edges engage into the guides 13 and 14 and are guided in a straight line movement thereby. The slide 15 carries a pin 16 which projects thru a slot 17 in the bracket 1 and carries on the outside thereof the combined knob and latch 18.

The slide 15 located at the back of the bracket 1 is provided at the top with a hook shaped lug 19 and into this lug engages the end of the bow spring 20. The bow spring 20

is bent and placed into the back of the bracket 1 so as to normally lift the slide 15 and thus yieldingly hold the combined knob and latch 18 in its elevated position. As illustrated in Figures 2, 4 and 5 the inside of the top of the combined knob and latch 18 is slightly cut away at 21 to present an angular flat surface with which the outer end of the locking plate 2 engages to hold it in its inoperative position. In order to bring the locking plate into this inoperative position it is swung down from the horizontal position illustrated in Figures 1 and 2 until the outer end of the locking plate strikes the curved outer surface of the combined knob and latch. By forcing the locking plate against the knob 18, the knob is depressed until the outer end of the locking plate has moved from the curved front of the knob to the cut away rear 21 thereof which allows the knob 18 to be forced up again by its spring 20 and thus hold the locking plate 2 in a vertical position in front of the bracket 1.

The locking plate is spring operated and when released by the combined knob and latch 18 immediately swings outwardly and upwardly against the key so that the yielding pressure exerted by the locking plate holds the handle of the key in a horizontal position from which it cannot be turned until the locking plate is again moved away from it. The spring for operating the locking plate in this manner is an extension of the bow spring 20 which, as illustrated in Figure 3, extends upwardly and is first wound around one of the pivot pins 10 and then looped with the loop 23 over the back of the locking plate 2 to the other of the pivot pins 10. After being wound around the second pivot pin it extends down along the back of the bracket 1 where its end is bent at right angles so as to engage and anchor itself behind the guides 13 and 14. In order to show the spring clearly, especially the loop 23 thereof, the locking plate 2 is shown in dotted lines in Figure 3 in a position in line with the bracket 2. This figure also shows that the locking plate 2 is also slotted in the middle and that the slot in the locking plate 2 forms a continuation of the slot in the bracket 1. As these slots are located directly in front of the key hole in the escutcheon the web of the key is free to be inserted or withdrawn from the key hole when the locking plate is placed in its inoperative position illustrated in full lines in Figure 4 and in dotted lines in Figures 1 and 2. After the key has been inserted and has been turned to lock the lock, the bow or handle thereof is placed in an approximately horizontal position. The locking plate 2 is then released by depressing the combined knob and latch 18. The loop 23 of the spring which operates the locking plate then forces the locking plate to swing outwardly and upwardly until it rests

against the under side of the key and yieldingly holds it in a horizontal position. The pressure of the spring is sufficient to prevent a turning of the key from the outside of the door so that it cannot be pushed out of the lock and the lock opened from the outside by means of a duplicate key or other instrument designed for opening locks.

I claim:

1. A key guard comprising a vertical bracket with a central slot in the upper end thereof, a rearwardly projecting hook shaped lug at the bottom of said slot adapted to engage over the lower end of the key hole in an escutcheon and anchor the upper end of said bracket in place in front of the escutcheon, fastening means for fastening the lower end of said bracket below the escutcheon plate to anchor said bracket, and a spring pressed locking plate mounted to swing on the upper end of said bracket. 75
2. A key board comprising a vertical bracket, a spring operated locking plate mounted on said bracket, combined anchoring and locating means for anchoring and locating said bracket to the escutcheon with relation to the key hole therein, and fastening means for fastening said bracket in place below the escutcheon. 80
3. A key guard comprising a vertical bracket, a latch plate mounted to slide at the back of said bracket, a latch carried by said latch plate, a locking plate mounted to swing on said vertical bracket, said locking plate being adapted to be held in its inoperative vertical position by said latch and spring pressed means for swinging said locking plate from its inoperative position into engagement with the key on the release thereof by said latch. 85
4. A key guard for a lock having an escutcheon with a key hole therein and comprising a vertical bracket, anchoring means for anchoring said bracket to said escutcheon and locate the said bracket in a predetermined position in front of said escutcheon with relation to the key hole provided therein, fastening means on said bracket to fasten said bracket in place below said escutcheon and prevent the disengagement of said anchoring means from said escutcheon, a spring pressed locking plate mounted to swing on said bracket and spring pressed latching means for holding said locking plate in an inoperative vertical position in front of said bracket, said spring pressed locking plate being adapted to swing into engagement with the handle of a key located in the key hole when released by said latching means to hold the handle of the key in a predetermined position and hold the key against axial movement in the key hole. 90
5. A key guard for a lock having an escutcheon with a key hole, comprising a vertical bracket having a slot in the upper end 95

thereof, a rearwardly projecting hook shaped lug at the bottom of said slot and adapted to engage over the bottom of said key hole, fastening means at the bottom of said bracket to fasten said bracket in place below said escutcheon and hold said hook shaped lug in place in said key hole, a latch plate mounted to slide in back of said vertical bracket, a latch carried by said latch plate, a locking plate having a slot at the inner end thereof and mounted to swing on said vertical bracket with its slot in line with the slot in said vertical bracket, spring pressed means for swinging said locking plate outwardly into engagement with the key hole to yieldingly hold said key against axial movement in said key hole, and spring pressed means for yieldingly holding said latch plate to have said latch engage the outer end of said locking plate when swung away from the key into a downwardly vertical position in front of said bracket.
